UNITED STATES PATENT OFFICE.

FRED. W. GORDON, OF PITTSBURG, PENNSYLVANIA.

TUYERE.

SPECIFICATION forming part of Letters Patent No. 295,540, dated March 25, 1884.

Application filed November 26, 1883. (No model.)

To all whom it may concern:

Be it known that I, FRED. W. GORDON, of Pittsburg, Allegheny county, Pennsylvania, have invented certain new and useful Improvements in Tuyeres, of which the following is a specification.

This invention pertains to tuyeres for blast-furnaces; and it relates particularly to the arrangement of the tuyere-pipe junction, as hereinafter described and distinctly claimed.

Figure 1 in the accompanying drawings is a vertical section at the breast of a blast-furnace, showing my improved tuyere in position. Fig. 2 is a rear elevation of the tuyere.

In the drawings, A represents a portion of the wall at the breast of a blast-furnace; B, a water-cooled tuyere-breast in said wall; C, the tuyere fitting the tuyere-breast joint and protruding into the furnace; D, the water-pipes of the tuyere; E, the windway through the center of the tuyere; F, the tuyere-pipe; G, the water-jacket of the tuyere; H, centering-

lugs on the rear face of the tuyere for supporting the separable tuyere-pipe concentric with the tuyere; I, the taper fit of the tuyere in the tuyere-breast; J, a shell-like extension of the outer periphery of the tuyere around the end of the tuyere-pipe and around the water-pipes entering the water-jacket of the tuyere; K, a clay-holding space around the end of the tuyere-pipe and within the shell J. The tuyere-pipe is packed at the tuyere by clay held in the parallel concentric space K.

I claim as my invention—

The combination of water-cooled tuyere C, water-pipes D, centering-lugs H or their equivalents, and the rear shell, J, at the external periphery of the tuyere, outside of the water-pipe, substantially as set forth.

FRED. W. GORDON.
